CLAIM

The ornamental design for a surface configuration of forklift, toy, and/or other replicas, as shown and described.

DESCRIPTION

This application is related to the following co-pending applications: application Ser. No. 29/262,038, entitled “Surface Configuration of a Forklift, Toy, and/or Other Replicas;” and application Ser. No. 29/262,037, entitled “Surface Configuration of a Forklift, Toy, and/or Other Replicas.”

FIG. 1 is a right side view of a surface configuration of a forklift, toy and/or other replicas according to my novel design;

FIG. 2 is a left side view thereof;

FIG. 3 is a rear view thereof; and,

FIG. 4 is a front view thereof.
